CLAIM

The ornamental design for an inspection fixture for use in inspecting the mounting of contact lens within a tinting fixture prior to tinting, as shown and described.

DESCRIPTION

FIG. 1 is a perspective view of an inspection fixture for use in inspecting the mounting of contact lens within a tinting fixture prior to tinting, showing my new design; FIG. 2 is a top plan view thereof;

FIG. 3 is a right side elevational view thereof;

FIG. 4 is a front elevational view thereof; and

FIG. 5 is a left side elevational view thereof; and

FIG. 6 is a rear elevational view thereof.
